(57) **CLAIM**

The ornamental design for a lampshade, as shown and described.

DESCRIPTION

FIG. 1 is a perspective view of a lampshade, showing a first embodiment of my new design;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a cross-sectional view of the indicated section —9— shown in FIG. 4;

FIG. 10 is a perspective view showing a second embodiment of a lampshade;

FIG. 11 is another perspective view thereof;

FIG. 12 is a front elevation view thereof;

FIG. 13 is a rear elevation view thereof;

FIG. 14 is a left side elevation view thereof;

FIG. 15 is a right side elevation view thereof;

FIG. 16 is a top plan view thereof;

FIG. 17 is a bottom plan view thereof; and,

FIG. 18 is an enlarged view of the indicated section —18— shown in FIG. 13.
